[57] CLAIM

The ornamental design for combined card reader and display for a bus fare adjustment system, as shown and described.

DESCRIPTION

FIG. 1 is a top, front, right side perspective view of a combined card reader and display for a bus fare adjustment system showing my new design.

FIG. 2 is a right side elevational view thereof, a left side being a mirror image of the right;

FIG. 3 is a top plan view thereof;

FIG. 4 is a front elevational view thereof;

FIG. 5 is a rear elevational view thereof; and

FIG. 6 is a bottom plan view thereof.

The broken lines are shown in FIG. 1 for illustrative purposes only.

FIG. 1

FIG. 2

FIG. 3

FIG. 4

FIG. 5

FIG. 6
